[57] CLAIM

The ornamental design for a crimping tool, substantially as shown.

DESCRIPTION

FIG. 1 is a side elevation of a crimping tool showing our new design;

FIG. 2 is a top plan view thereof;

FIG. 3 is a side elevation thereof but taken from the opposite side to FIG. 1;

FIG. 4 is a bottom plan view thereof;

FIG. 5 is a front end elevation thereof;

FIG. 6 is a rear end elevation thereof.
